MILLER REESE HUTCHISON, OF WEST ORANGE, NEW JERSEY, ASSIGNEE TO LOVELL-McCONNELL MANUFACTURING COMPANY, A CORPORATION OF DELAWARE.

DIAPHRAGM-HORN.

1,131,635.

Specification of Letters Patent.

Patented Mar. 9, 1915.

Application filed May 11, 1911. Serial No. 626,489.

To all whom it may concern:

Be it known that I, MILLER REESE HUTCHISON, a citizen of the United States, and resident of West Orange, in the county of 5 Essex and State of New Jersey, have invented certain new and useful Improvements in Diaphragm-Horns, of which the following is a specification.

This invention relates to that kind of mechanically actuated diaphragm horns in which the diaphragm is vibrated bodily by high speed mechanism, such as a shaft or rotary member driven by an electric motor and provided with an eccentric portion or 15 cam faces adapted to transform rotary into reciprocatory movement.

In my co-pending application Serial No. 626,487, filed May 11, 1911, I have described various useful features of design and operation for securing cushioned actuation of the diaphragm, referring more particularly to different forms of diaphragm-coupled cushioning members for partially absorbing and partially transmitting the efforts exerted by 25 the rotary driver. The constructions and arrangements forming the special subject-matter of this application are illustrated and described in my said application as coming within the broad scope thereof, and 30 one form of construction shown herein and covered by the appended claim is shown and described, but not specifically claimed, in my prior application Serial No. 494,688, filed May 7, 1909, namely the form of signal 35 employing a hollow cylinder of spring steel as a thrust member between the rotary driver and the diaphragm.

The object of this invention is to provide a non-rigid member between and separate 40 from the rotary driver and diaphragm for receiving the thrust or impact from the former and transmitting the impulse to the latter in a more or less yielding manner. Preferably the member is so constructed and arranged as to yield at each normal effort exerted by the driver, so as to absorb part of the power during the first part of the duration of the thrust and thereby cushion the action and temper the impact upon the diaphragm. The possible embodiments of such means are numerous, but I prefer to construct the member as a loose connection 45 movable in a guide intermediate the driver and the diaphragm under the alternate actuation thereof.

In the accompanying drawing, illustrating the invention: Figure 1 is a view, partly in side elevation and partly in section, of a horn signal embodying one form of the invention; Fig. 2 is a horizontal section 60 through the rear part of the signal; Fig. 3 is a detail view of the connection in its guide; and Fig. 4 is a view like Fig. 2 showing another form of yielding thrust connection.

The numeral 1 indicates the horn or resonator, carried by the front section 2 of the diaphragm case. The diaphragm 3 is held between cork washers or the like 4, 5, by the marginal clamping portions 6, 7 of the front section 2 and the rear section 8 of the diaphragm case. The clamping is effected by screws 9, which pass through openings in the clamping portions of the case sections and in the gaskets and the marginal region of the diaphragm.

The rear section 8 of the case is formed to receive the rotary driver 10, which is shown as a disk provided with a plurality of peripheral cam projections 11. Preferably, the axis of this rotary driver is parallel to the diaphragm, as shown. Suitable means for rotating the driver at high speed is illustrated in the form of an incased electric motor 12, the armature shaft 13 of which is prolonged into the rear section of the diaphragm case, there carrying the rotary driver. The driver is preferably solidly mounted so as to deliver rigid thrusts to the yieldable or cushioning connection. The bearing sleeve 14 of the rigid shaft 13 is 60 rigidly held in the rear section of the diaphragm case, and has exterior cylindrical bearing upon the case at 14^a, 14^b, the axis of the shaft being eccentric to said cylindrical bearing surfaces so that rotary adjustment 65 of the sleeve serves to adjust the cam to or from the diaphragm. The yieldable actuating connection may be positioned in a variety of ways, but the simplest arrangement is that shown wherein it is directly interposed between the rotary cam 10 and the diaphragm 3 or a wear piece or projection 16 thereon. Preferably, also, the connection is separate from the diaphragm and the mechanical actuating means, being loosely 100 movable therebetween.

In Figs. 1 to 3 the connection or intermediate thrust member is shown as being embodied in the form of a hollow cylinder 15 of spring steel or other suitable resilient

material, disposed with its axis parallel to the axis of the rotary driver 10. This hollow cylinder is mounted in a suitable stationary guide 20, wherein it is moved back and forth under the alternate actuation of the driver and the diaphragm. These views illustrate the fact that the diaphragm may, if desired, be provided with a wear piece 16 for receiving the impulse from the intermediate loose connection. Preferably the said loose connection normally contacts with both the diaphragm and with the cams or projecting portions of the driven part and as will be seen from Fig. 2, the member 15 and the guides 20 are designed with reference to the amplitude of possible vibration of the diaphragm and the depths of the depressions between cams, so that the guides 20 will engage the member 15 and hold the same from lateral displacement throughout the extreme range of movement made possible by the cam depressions and the vibration of the diaphragm.

In Fig. 4 the loose cushioning connection is shown in the form of a longitudinally reciprocable plug 15^a of fiber or other suitable semi-yielding material, slidably mounted in a suitable stationary guide 20^a. This form of device illustrates the fact that a special wear piece may be dispensed with entirely, the fiber member constituting a sufficient wear piece for receiving the thrusts of the rotary driver and applying the impulses directly against the face of the diaphragm.

In operation, the loose connection is preferably so constituted as to yield somewhat under each normal diaphragm-displacing effort of the driver. In this way, the thrusts are softened or tempered before reaching the diaphragm, so that the latter is set in motion or the direction of its motion is changed less abruptly than in those cases where the diaphragm is rigidly driven.

It will be understood that in all cases I

prefer to have my above described loose connection only sufficiently yieldable to temper the impact of the power impulses derived from the cam and applied to vibrate the diaphragm, but not sufficiently yieldable to decrease the vibration and impair the volume of sound which is necessary for an efficient warning signal. Hence, it will be understood that the cushioning is preferably such as will be sufficient to absorb or cushion the concussive effects of the cam without seriously modifying or impairing the transmission of positive cam thrusts through a desired range of movement of the diaphragm and while still maintaining the advantages of the loud sound producible by my well known method of mechanically and positively forcing each outward bodily movement of the diaphragm beyond its normal position to a pre-determined position at such velocity as to cause further outward movement of the diaphragm in the same direction by reason of its inertia and against increasing elastic stress.

I claim:

In an alarm or signaling device, the combination of a diaphragm, a rotor presenting a series of camming projections, high speed means for driving said rotor, a guide member disposed between said rotor and said diaphragm and having an aperture therethrough and a loose concussion-cushioning, thrust-transmitting member disposed within said aperture and adapted to receive and cushion the thrust from the rotor and apply the impulses to the diaphragm. 80

Signed at New York city, in the county of New York, and State of New York, this 9th day of May, A. D. 1911.

MILLER REESE HUTCHISON.
